CHANNEL RELAY CONNECTING AND
INTERLOCKING SYSTEMChester A. Rackey, Westport, Conn., assignor to
Radio Corporation of America, a corporation of
Delaware

Application March 29, 1934, Serial No. 717,889

9 Claims. (Cl. 179—1)

The present invention relates to a system for connecting one of a great number of program studios or sources to a two wire channel which may be in turn connected to a telephone line, 5 transmitter or any other utilization circuit, and for inhibiting the simultaneous connection of more than one studio to said channel.

Broadcasting systems in use today involve a plurality of studios or program sources, and a 10 plurality of channels or telephone lines running from said sources to transmitters or other utilization circuits. The programs sent out from the studios to the channel or channels and from thence to the transmitters or utilization circuits 15 are synchronized in that a plurality of programs at the various studios commence at the same time. By "the same time" it is meant that they start exactly on the same second. Obviously where several studios are to be hooked to one 20 or more channels which are in turn connected with transmitters or other utilization circuits there is danger of connecting more than one studio to the same channel.

An object of the present invention is to provide 25 a novel relay system including interlocking connections which prevents more than one studio from being connected to the same channel simultaneously. If more than one studio were connected, to the same transmitter channel, at the 30 same time the programs would be mixed and this would result in the transmission of unintelligible signals.

An object of the present invention is to include 35 in this novel program distribution system means for preventing more than one studio to be connected to a particular channel at the same time due to chattering of the contacts for any reason.

In its briefest aspect my invention involves 40 what I have termed a channel relay and a set-up relay for each studio or program source. The channel relays and set-up relays may be located 45 in any convenient place at or remote from the program sources. The system also includes an interlocking and bridge current relay for all of the channel relays and set-up relays and a bridge circuit having three arms composed of fixed resistances and a fourth arm which is normally disconnected from the bridge circuit. The fourth arm comprises a plurality of resistances equal in 50 value to the resistances of the other arms. There is a resistance in the fourth arm for each channel relay and when one of said resistances is connected into the bridge, the bridge is balanced. A diagonal of the bridge includes a relay which 55 when energized breaks the circuit between the

channel relays, set-up relays, etc. and the source energizing said relays. If any two of said resistances are connected in the bridge circuit simultaneously the bridge circuit is unbalanced, current flows in the diagonal and the circuit for 5 energizing the relays becomes broken and all of the relays return to their normal position.

Normally, that is, when all of the studios are disconnected from the channel, the bridge circuit is obviously unbalanced. In order to prevent this 10 initial unbalancing of the bridge circuit from interrupting the relay energizing circuit, thereby preventing normal operation of the relays when an operator closes a channel relay key I provide a pair of normally open contacts which interrupt 15 the energizing circuit for the bridge, which circuit is connected across the other pair of diagonals of the bridge. This last named pair of contacts is closed on closing a set-up button to complete the bridge energizing circuit immedi- 20ately after a resistance is included in the fourth arm of the bridge, so that the bridge first becomes balanced and then energized as a single 25 studio or program source is connected to the channel, or becomes energized and unbalanced the instant more than one studio or program source is connected to the channel. In the former case nothing happens, that is, the single studio remains connected to the channel and the program goes out in the desired manner. In the latter case the bridge is unbalanced, current flows 30 through the diagonal thereof and the relay energizing source is disconnected from the relays which all return to their normal positions.

Many other objects of my invention and ad- 35 vantages flowing from the use thereof will appear from the following detailed description thereof and therefrom when read in connection with the attached drawing in which the single figure il- 40 lustrates diagrammatically the essential features only of my system. Of course I contemplate the inclusion in my system of any necessary ad- 45ditional apparatus or refinements in general use.

Referring to the drawing A, B, C, D and E are studio relay units, each of which may be 45 connected as shown by lines to a corresponding studio, there being a studio relay unit for each studio or source of programs of the system. Studio relays A, B and C are represented by rec- 50 tangles but the relays in these studios may be the same as the relays shown more in detail in the studio relays D and E. While it will be under- 55 stood that there may be a great number of studios and studio relays, in order to simplify the description of the apparatus I have shown three

studio relays diagrammatically and two studio relays in details. The studio relays when actuated operate in accordance with my present invention to connect the selected studio by way of the studio relays to a telephone or transmitter line TL.

The relays in each studio relay unit includes a channel relay 5, including a magnetic winding, normally open contacts 17 and 18 and normally closed contact 24. Each studio relay unit includes also a "set-up relay" comprising a magnet 7 and normally open contacts 25, 26 and 23. The entire group of studio relay systems cooperate with a bridge circuit having three equal resistive arms 11, 12 and 13 and a fourth arm normally open-circuited. The fourth arm may be composed of any one of a number of resistances 14, 15 etc. equal in value to the other arms in the bridge circuit. Each of the resistances 20 in the fourth arm are adapted under conditions to be described more in detail later to be included in the bridge circuit. When the arm is so included in the bridge circuit, the bridge is balanced and even though current is applied from 25 the high potential source across the bridge there will be no potential difference across the diagonal thereof, and therefore no current will flow in the relay winding 10 connected in the circuit between the relay operating battery RB and the 30 energizing circuits of the studio relays. My system also includes an interlock and bridge current relay comprising normally closed contacts 29 and normally open contacts 30. The normally open contacts 30 are in series with the bridge source 35 BS connected across the diagonals of the bridge circuit. My system therefore includes a channel relay and set-up relay for each studio involved and a balanced bridge current relay for the entire group of studio relays associated with a single channel.

As pointed out above, the contacts 17 and 18 of the channel relay and 23, 25 and 26 of the set-up relay of studio D relays are normally open. Contacts 19 and 20 of the channel relay and 21, 45 27 and 28 of the set-up relay of studio E relays are normally open. Contacts 24 of the channel relay of studio D relays and contact 22 of the channel relay of studio D relays are normally closed. The set-up buttons 1 and 2 of studio 50 D and E relays respectively are normally open, while the release keys 3 and 4 of studios D and E respectively are normally closed. Contact 29 of the interlock and bridge current relay is normally closed while contact 30 is normally open. The 55 contact 31 of the relay in the diagonal of the bridge circuit is normally closed.

At this point it will be noted that since the relay contacts 23 and 21 of studio D relays and studio E relays respectively, and in any of the 60 other relays in the system are open the bridge circuit includes only three arms and therefore is unbalanced. While this is true, however, the circuit through the winding 10 does not become energized because the contacts 30 are normally 65 open, thereby breaking the circuit through the source BS connected to the diagonals of the bridge. This prevents the winding 10 from being energized and the contacts 31 from being opened to thereby interrupt the circuit between the relay energizing source RB and the windings in said 70 relays.

It will now be assumed that the operator desires to connect the studio D to the line TL running to a transmitter or other utilization circuit. This is 75 accomplished by closing the set-up key or button

1. This closes a circuit through the winding 7 by way of contacts 24, winding 1, normally closed release key 3 to ground, to the positive terminal of battery RB, negative terminal of battery RB, normally closed contact 31, normally closed contact 29, and back to set-up button 1. Current flows in the winding of 7 to energize the same and close normally open contacts 25 and 26.

Closing normally open contact 26 energizes the winding of relay 5 by way of 26, lead 40, with the winding of 5, ground, the positive terminal of battery RB, the negative terminal of the battery RB, normally closed contact 31, lead 41, closed contacts 25, lead 42 and back to contact 26.

Closing the contacts 25 completes a circuit through the winding of relay 9 by way of contacts 25, lead 43, the winding 9, of the interlock relay, ground, the positive terminal of the relay energizing source RB, the negative terminal of said source, normally closed contacts 31 and lead 41 to contacts 25.

Now we have the windings 5 and 7 of channel and set-up relays and winding 9 of interlocking bridge current relay energized. These relays now 25 act to close normally open contacts 17, 18 and 23 and open normally closed contact 24 at the channel relay of studio D relays and to open normally closed contact 29 and close normally open contact 30 of the interlock and bridge current relay.

Closing contacts 17 and 18 connects studio D to the outgoing telephone or transmission line TL. Closing 23 connects one of the resistances, in this case resistance 15, in the fourth arm of 35 the bridge circuit by way of contacts 23 and ground. The bridge is now balanced and the closing of contacts 30 following closing of contacts 25 completes the circuit between the battery BS and the diagonals of the bridge.

The action of the relay 5 in opening normally closed contact 24 interrupts the circuit between the winding of 7 and the source RB at 24. In order to maintain the winding of 7 energized in spite of this opening of the contacts 24 so 45 that the studio D will remain connected to the lines TL until disconnected therefrom by an act of the operator, I provide a holding circuit by way of contacts 25 which are now closed. This circuit includes the right hand contact of contacts 25, the winding 7, release key 3, ground, the positive terminal of source RB, the negative terminal of source RB, normally closed contacts 31, lead 41, and the center contact of contacts 25.

Now we have studio D connected to the outgoing channel TL. Relays 5, 7 and 9 are energized and the bridge circuit is energized and balanced. The system may at any time be returned to its original state by opening release key 3.

If for some reason that is due to chattering or 60 an act of the operator one of the other studio relay set-up buttons as, for example, set-up button No. 2, is closed at the same time that set-up button No. 1 was closed the channel relay winding 6 and set-up relay winding 8 of studio E will 65 operate in the same manner in which the corresponding relays at studio D operated, as pointed out hereinbefore in detail, to connect studio D to line TL and simultaneously connect an additional resistance, say 14, in the fourth arm of the 70 bridge circuit. When the contacts 21 of the channel relay in studio E closes to connect resistance 14 in the fourth arm of the bridge, the bridge circuit becomes unbalanced since the resistance in the fourth arm is now not equal 75

to the resistance in the remaining arms. The bridge is unbalanced and an energizing current flows in the winding of relay 10. This relay when energized opens normally closed contact 5 31 whereby interrupting the circuit between the source RB and all of the relay windings in the relay systems of the various studios. This returns all relays and contacts of the various studios to their normal position so that no studios 10 are connected to the transmission line or transmitter line TL.

Only one of a great number of studios as shown, or not shown, may be connected to the line TL.

Briefly then applicant has provided a novel and 15 simplified means for connecting any one of a plurality of studios to a transmission line. This means includes a holding circuit which maintains said studio so connected to said transmission line until the operator at the studio relays actually 20 opens the release key to de-energize the set-up relay winding. The system also includes means for preventing more than one studio from being connected simultaneously to the transmission channel either by simultaneous acts of operators, 25 or due to vibration or chattering or other weaknesses in the apparatus. The system includes a balanced bridge circuit and also includes means for insuring that the bridge circuit is not energized until the relays have had time to insert the 30 fourth arm of the bridge so that the bridge is balanced when energized and therefore does not open the relay energizing circuit. Indicating lights, consisting of small switchboard lamps located immediately above the set-up key and energized in multiple with one of the studio relay 35 windings, may indicate to the operator when his channel has been properly set up.

Having thus described my invention and the operation thereof, what I claim is:

40 1. A broadcasting system comprising, a transmission line and a plurality of program sources, a separate relay for connecting each of said sources to said line, and means for returning said relays to normal position when more than one 45 of said studios are connected simultaneously to said line including a bridge circuit which is balanced and energized by the operation of one of said first named relays and unbalanced when more than one of said relays are actuated to de- 50 energize all of said relays.

2. The combination with a plurality of program sources and a transmission line, of a bridge circuit having three arms, a channel relay for each of said sources, a plurality of circuits arranged 55 to be connected in the fourth arm of said bridge when said relays are energized, there being a circuit for each of said sources, contacts associated with each of said relays and said sources and line for connecting a selected one of said 60 sources to said transmission line, and for connecting one of said circuits in the fourth arm of said bridge to balance the same, and a relay connected in the diagonal of said bridge and associated with an additional circuit for energizing said 65 channel relays to interrupt the same when more than one circuit is connected in the fourth arm of said bridge to unbalance the same.

3. The combination with a plurality of program sources and a transmission line, of a bridge circuit having three arms, a channel relay for each of said sources, a circuit for energizing said channel relays, a circuit for each of said sources including an additional resistance which is connected in the fourth arm of said bridge to balance 70 the bridge when the corresponding relay is ener-

gized, contacts associated with each of said channel relays for connecting a selected one of said studios to said transmission line, and a restoring relay connected in the diagonal of said bridge and associated with the energizing circuit for said channel relays to interrupt the same when more than one of said channel relays are operated to connect more than one of said resistances in the fourth arm of said bridge. 5

4. In combination with a plurality of program sources and a transmission line, of means for connecting a selected one of said sources only to said line comprising, a channel relay for each source, contacts cooperating therewith and with said transmission line and with lines connected 15 to the program source associated therewith, a bridge circuit, said bridge circuit having three resistive arms, a plurality of resistances, there being a resistance for each of said program sources, a set-up button adapted when closed to 20 energize the winding of said channel relay, contacts connected with said channel relay for connecting the selected one of said program sources to said transmission line, another set of contacts associated with said set-up relay and adapted 25 when closed to connect the resistance associated with said selected program source in the fourth arm of said bridge whereby said bridge is balanced, and an additional relay energized by closing said set-up button for applying energizing 30 potentials to the diagonals of said bridge.

5. In combination with a plurality of program sources and a transmission line, of means for connecting a selected one of said sources only to said line comprising, a channel relay for each source, 35 contacts cooperating therewith and with said transmission line and with lines connected to the program source associated therewith, a set-up relay for each source, a bridge circuit, said bridge circuit having three balanced arms, a plurality 40 of circuits each of an electrical value sufficient to comprise the fourth arm of said bridge, there being a circuit for each of said program sources, a set-up button adapted when closed to energize the winding of said set-up relay, contacts connected 45 with said set-up relay for completing an energizing circuit for said channel relay whereby said contacts cooperating with said channel relay for connecting the selected one of said program sources to said transmission line are closed, 50 another set of contacts associated with said set-up relay and adapted when closed to connect one of said plurality of circuits corresponding with said selected program source in the fourth arm of said bridge whereby said bridge is balanced, and 55 an additional relay energized by a circuit completed by said set-up button for applying energizing potentials to the diagonals of said bridge.

6. In combination with a plurality of program sources and a transmission line, of means for connecting a selected one of said sources only to said line comprising a channel relay for each source, contacts cooperating therewith and with said transmission line and with lines connected to the program source associated therewith, a set-up relay for each source, a bridge circuit, said bridge circuit having three arms, a plurality of resistances, there being a resistance for each of said program sources, a set-up button for each source adapted when closed to energize the winding of 70 the corresponding set-up relay, contacts connected with said set-up relay for completing a holding winding therethrough for energizing said channel relay whereby said contacts connected with said channel relay are closed to connect the 75

- selected one of said program sources to said transmission line, another set of contacts associated with said set-up relay and adapted when closed to connect the resistance associated with 5 said selected program source in the fourth arm of said bridge whereby said bridge is balanced, an additional relay for applying energizing potentials to the diagonals of said bridge, and a relay in the diagonal of said bridge for returning all of 10 said aforesaid relays to normal if more than one of said resistances are connected in the fourth arm of said bridge.

7. The combination with a plurality of program sources, and a transmission line, of means 15 for connecting a selected one of said sources to said line comprising, a relay system for each of said sources, each relay system comprising a channel relay, a set-up relay and a set-up button and a release key, an interlocking-bridge current 20 relay for each group of studio relays, a bridge circuit for each group of studio relays associated with a particular channel, said bridge circuit comprising three balanced arms, a plurality of resistances each equal to the resistance in one 25 arm of said bridge there being a resistance for each studio, a circuit including the set-up buttons for energizing the set-up relay of each studio, contacts associated with said set-up relay for closing a holding winding therethrough and for 30 energizing the corresponding channel relay winding, contacts associated with said channel relay winding for completing a circuit connecting the selected one of said program sources to said transmission line, contacts associated with said set-up 35 relay winding for connecting one of said resistances in the fourth arm of said bridge, contacts connected with said set-up relay winding for com-

pleting a circuit through said interlock and bridge current relay, contacts associated with said interlock and bridge current relay winding for completing a circuit connecting a source of potential across the diagonals of said bridge circuit, a relay connected across the other diagonal of said bridge circuits, normally closed contacts associated with said relay, said contacts normally completing a circuit between an energizing source and said channel relays, set-up relays and interlocking bridge current relays, whereby when more than one of said set-up buttons are closed simultaneously more than one of said resistances will be included in the fourth arm of said bridge and said bridge circuit will be unbalanced and energized and current will flow in said diagonal, thereby interrupting the circuit between all of said relays and said energizing source thereby returning all of said relays and contacts to their normal position. 5 10 15 20

8. A signalling system comprising, a transmission line and a plurality of signal sources, separate means for connecting any selected one of said sources to said line, and common means for returning said connecting means to normal position when more than one of said sources are connected simultaneously to said line. 25

9. In a relay system to be utilized with a broadcasting system comprising a transmission line and a plurality of studios, relay means and circuits to be completed thereby for connecting a selected one of said studios to said line, and relay means for returning said first named relay means and said circuits to normal position when more than one of said studios are connected simultaneously to said line. 30 35

CHESTER A. RACKEY.
